UNITED STATES PATENT OFFICE.

ALFRED BODE AND KARL BÖTTCHER, OF BENRATH, NEAR DÜSSELDORF,
GERMANY.

TURNING-SHOVEL DREDGER.

SPECIFICATION forming part of Letters Patent No. 787,022, dated April 11, 1905.

Application filed January 12, 1905. Serial No. 240,758.

To all whom it may concern:

Be it known that we, ALFRED BODE and KARL BÖTTCHER, engineers, subjects of the German Emperor, and residents of Benrath, near Düsseldorf, in the Province of the Rhine, German Empire, have jointly invented certain new and useful Improvements in Turning-Shovel Dredgers, of which the following is an exact specification.

Our invention relates to improvements in turning-shovel dredgers, and has for its purpose to provide means for closing the shovels with as much power as possible. For this purpose the shovels are actuated by pressure-rod, which are so connected to the lower pulley-traverse that these rods work in closing the shovels as knee-levers, thereby obtaining a considerable closing power.

In order to make our invention more clear, reference is made to the accompanying drawings, in which—

Figure 1 shows a front view of a convenient device of our invention. Fig. 2 shows a side view. Fig. 3 shows another side view in which the shovels are shown in open position.

In the drawings, *a* represents the shovels mounted on the frame *b*, the upper fixed traverse *c* of which carries the pulley *d*. The lower traverse *e* carries the rollers *f* and is guided sidewise by the guides *g*, so as to allow an up-and-down movement of the traverse *e*. The shovels *a* are journaled in the frame at *a'*, the side plates or front walls of said shovels *a* being extended above the journals *a'*.

h h are pressure-rods connected at one of

their ends to the upper part of the shovels at *a'*, whereas the other ends of these rods *h* are connected to the traverse *e*. If this latter is moved down, the shovels are opened, whereas 40 they are again closed if the traverse *e* is raised and moved into the position shown in Fig. 1.

Having thus fully described the nature of our invention, what we desire to secure by Letters Patent of the United States is—

1. In a turning-shovel dredger, the combination of a frame, with two shovels pivotally mounted therein, a traverse guided in this frame, outwardly-directed rods, connected with one end to the shovels and with the other 50 end to the traverse, and means for moving said traverse up and down thereby closing and opening the shovels, substantially as described and for the purpose set forth.

2. In a turning-shovel dredger, the combination of a frame, with two shovels pivotally mounted therein, the front walls of the shovels being upwardly continued over their pivots, a traverse guided by the frame, outwardly-directed rods connected with one end to the 60 upper part of these walls and with the other end to said traverse, and means for moving said traverse up and down, thereby opening and closing the shovels, substantially as described and for the purpose set forth.

In witness whereof we have hereunto set our hands in the presence of two witnesses.

ALFRED BODE.
KARL BÖTTCHER.
